UNITED STATES PATENT OFFICE

ARTHUR RALSTON STALB, JR., OF FARMINGDALE, NEW YORK

DETACHABLE SKI

Application filed May 9, 1928. Serial No. 276,289.

This invention relates to aircraft in general, and, in particular, to a new and improved landing means therefor.

In practice it has been found desirable at 5 times to land an aeroplane upon the surface of snow or ice. Hitherto it has been customary to replace the usual floats with which seaplanes may be provided or the wheels of land planes with skis for the purpose of 10 permitting the use of the aeroplane during the winter months or in a very cold climate. The removal of the usual running gear makes it impossible to land the aeroplane on any other surface than snow or ice without danger 15 of serious damage to the running gear and frame.

The general object of this invention is to provide a means for landing an aeroplane on the surface of snow or ice or upon any smooth 20 surface.

A more specific object of this invention is to provide a means for permitting a seaplane to land on the surface of snow or ice without interfering with the use of its pontoons for 25 landing on water.

Another object of this invention is to provide a resilient shock absorbing means for attaching a ski to the bottom of the pontoon of a seaplane.

Another object of this invention is to provide means for detachably mounting a ski on the landing gear of an aeroplane.

Other objects and advantages of this invention will become apparent from the following specification, claims and appended drawings, in which:—

Fig. 1 is a vertical elevation showing a ski attached to the bottom of an aeroplane pontoon.

Fig. 2 is a vertical longitudinal section showing the construction of the ski and the means for attaching it to the pontoon.

Fig. 3 is a transverse section taken on the line 3—3 of Fig. 1 and viewed in the direction of the arrows in that figure.

Fig. 4 is a vertical transverse view, partly in section, showing the construction of the resilient members.

Referring to the drawings and Figs. 1 and 2 in particular, the numeral 1 represents

a ski adapted to be attached to the bottom of a seaplane pontoon. The ski 1 may be constructed of any suitable material and in any desired manner but is shown in the drawings as being constructed of layers of wood 55 in order to secure both lightness and strength. Each of the skis 1 has the general shape shown in Fig. 2 and is detachably connected to the pontoon 2 in a manner now to be described.

Extending longitudinally along the bottom of each pontoon 2 and in spaced relationship with each other and to the front of the step are two angle bars 3 which are bolted or otherwise detachably fastened firmly to 65 the pontoon. The ski 1 lies between the two angle bars 3, as best shown in Figs. 1 and 3, and is pivotally attached to the angle bars by means of a bolt 4 which passes thru holes in the angle bars and also thru a hole in a 70 nose piece 5. The nose piece 5 is attached to the forward end of the ski 1 by means of plates 6 and bolts or screws 7. The whole purpose of this construction is to permit the ski 1 to rock about the bolt 4 as a pivot in 75 order to allow the ski to give in response to the shocks incidental to the landing of the seaplane on a relatively hard surface such as snow or ice. It is also desirable that the ski be so attached as to be readily removed 80 when not required or when repairs may be necessary.

In order to reduce the injurious effect produced by the shock of landing on snow or ice the rear ends of the skis are attached to the 85 bottoms of the pontoons by means of resilient members which act as shock absorbers. Any number of such resilient members may be provided and they may be placed in any desired position along the ski, but for convenience in description and to reduce the number of drawings, the ski shown and now to be described has been provided with only two resilient members connecting the rear end of the ski with the bottom of a pontoon. The resilient members are alike in all respects and a description of one will suffice for all.

Mounted upon the rear end of the ski 1 are pedestals 8 which are bolted firmly to the ski. Mounted upon and pivoted to the pedestals 8 100

are tubular members 9, which are pivoted to the pedestals by means of screw studs 10. The screw studs 10 pass thru holes in the pedestal 8, and holes in a reinforcing member 11 and screw firmly into holes in the tubular members 9. Each tubular member 9 is flared out or enlarged at its upper end as shown more clearly in Figs. 1 and 4.

Fitting smoothly within each tubular member 9 is a bushing or tube 12 which extends downwardly to a point just below the pivots 10 and is likewise flared out or enlarged so as to fit the flare in the tubular member 9. A tube 13 fits smoothly within the tube 12 and 15 is adapted to slide freely in an axial direction within the tube 12. A head piece 14 is provided for each tube 13 and is rigidly attached to tube 13 by means of any suitable nature as by a bushing 15 which passes thru holes in the 20 head piece 14 and the upper end of the tube 13. The head piece 14 may be threaded to the end of the tube 13 as indicated by the numeral 14' if desired.

Interposed between the head piece 14 and 25 the flared portions of tube 12 and tubular member 9 is a series of rings 16 which are constructed of any desirable resilient material such as rubber for instance, or, if deemed desirable, coil springs or air bags may be used 30 instead.

In order to hold the parts just described in their proper relationship when the seaplane is in flight a cable 17 is provided for each of the resilient members. The cable 17 passes 35 over the bushing 15 and is attached at both ends to an eye-bolt 18 by means of eyes formed in the cable which engage a short rod or stud which passes thru the opening in the eye-bolt as shown in Fig. 4. The eye-bolt 18 is ad- 40 justably supported by means of a member 19 which is mounted in a depression in the ski 1 directly beneath the pedestal 8. By means of a suitable adjusting screw 20 the slack in the cable may be taken up. The cable serves 45 to prevent the weight of the ski from pulling the parts out of relationship while the seaplane is in flight.

In order to provide greater strength and distribute the load more uniformly over the 50 ski 1 metal plates 21 have been shown inserted between the bottom and second layers of wood directly below the pedestal 8. The bolts which fasten the pedestals 8 to the upper surface of the ski 1 pass thru and bear against 55 these plates 21 and also pass thru holes in plates 22 upon which the pedestals rest. Plates 23 attached to the rear lower edge of the ski 1 serve to prevent splintering of the wood and prevent the excessive wear which 60 would otherwise occur at this point.

A bolt 25 passing thru bushing 15 and a hole in a bracket 26 attached to the bottom of the pontoon 2 serves to attach the resilient members to the bottom of the pontoon.

65 The whole purpose of the construction just

described is to absorb any shocks which may be caused by the skis striking the surface of ice or snow during the act of landing the aeroplane to which they may be attached. The shock is transmitted to the resilient material composing the rings 16 thru the pedestal 8, pivots 10 and the flared tubular members 9. The tube 13 serves to hold the parts in alignment and as a guide over which the tube 12 and tubular member 9 may slide. It will 70 be observed that the shape of the member 19 is such that a depression is formed in the ski into which the tube 13 may enter at times when a severe shock causes the compression of the resilient material and consequently 75 forces the lower end of the tube 13 downwardly toward the ski.

While a specific form of resilient member has been shown and described it is to be understood that it is not desired to limit the invention to the precise form shown in the drawings, but it is possible to use other forms 80 equally as well and to vary the position and number of resilient members at will to suit conditions met in service. It might also be 85 considered desirable at times to replace the resilient members just described with an air-bag or rubber blocks interposed between the ski and the bottom of the pontoon throughout the length or part of the length of the ski. 90

The plurality of shock absorbers at the rear of the ski effectually prevent sidesway of the ski owing to the length of the mounting pins and the slideby-side mounting of the absorber units. The channel members 3 also 100 help to prevent side displacement of the ski and carry a large part of the load incident to sideslip in landing to the pontoon shell and frame.

It will be clearly seen from a study of the 105 foregoing description and the attached drawings that this invention is admirably adapted to perform the function of a landing gear for use on ice or snow and at the same time does not interfere with the use of the pontoons in water landing. This invention makes it possible to use a seaplane for long trips from a warm climate where little ice or snow may be encountered to much colder climate where the presence of ice and snow and 110 absence of open water would make it impossible to land a plane without the risk of serious damage to the landing gear. Furthermore, the use of this invention permits the removal of the skis whenever desired without disturbing the rest of the landing gear and without preventing the use of the pontoons 115 for water landing.

Various changes in the construction of the 120 embodiment illustrated in the drawings may be made without departing from the spirit of the invention, and I do not therefore desire to limit myself to the specific construction shown and described but to interpret the in- 125 130

vention broadly within the scope of the appended claims.

What I claim as my invention is:

1. In a device of the class described, a water flotation body attached to and adapted to support the main body portion of the aircraft for landing on water, a plurality of members secured to the bottom of said body and forming a channel, and a ski positioned in said channel and pivotally secured to said members at its forward end.

2. In a device of the class described, a water flotation body attached to and adapted to support the main body portion of the aircraft for landing on water, a plurality of members secured to the bottom of said body and forming a channel, a ski positioned in said channel and pivotally secured to said members at its forward end and shock absorbing means between the ski and the body.

3. In a device of the class described, a flotation body attached to and adapted to support the main body portion of the aircraft for landing on relatively fluid mediums, a channel detachably secured to the bottom of said body, and a ski for landing on relatively solid mediums detachably secured in said channel.

4. In a device of the class described, a flotation body for landing on relatively fluid mediums, a channel detachably secured to the bottom of said body, a ski for landing on relatively solid mediums detachably secured in said channel, and shock absorbing means between said ski and said body.

In testimony whereof I affix my signature.
ARTHUR RALSTON STALB, JR.
